UNITED STATES PATENT OFFICE.

JUSTIN KAY TOLES, OF SAN FRANCISCO, CALIFORNIA.

WATER-HEATER.

1,218,965.

Specification of Letters Patent. Patented Mar. 13, 1917.

Application filed December 20, 1915. Serial No. 67,938.

To all whom it may concern:

Be it known that I, JUSTIN KAY TOLES, a citizen of the United States of America, residing at San Francisco, county of San Francisco, State of California, have invented a certain new and useful Water-Heater; and I do hereby declare the following to be a full, clear, and exact description of the invention, such as will enable others skilled in the art to which it appertains to make and use the same.

This invention relates to an improved water heater, and it may be said to consist in the provision of the novel and advantageous features and in the novel and improved construction, arrangement, and combination of parts and devices as will be apparent from the description and claims which follow hereinafter.

One object of the invention is to provide a novel and improved water heater in which the water moves in a thin layer or film in contact with a comparatively great area of the heating surface of the combustion chamber, and a very great proportion of the heat generated in the combustion is constrained to pass through the water and through a dead air space before it can pass to the atmosphere by radiation.

Another object of the invention is to provide a novel and improved water heater whereby the cold water is heated by causing it to pass in a thin layer or film through a chamber which is disposed between a combustion chamber and a dead air chamber or thermotic insulator.

Another object of the invention is to provide a novel and improved water heater in which three shells are constructed and arranged on a burner base to form a combustion space, a water space surrounding the combination space, and a dead air space surrounding the water space.

Another object of the invention is to provide a novel and improved water heater having a tank arranged in the dead air chamber surrounding the water chamber, so that the air is heated before it is mixed with the gas fuel.

Another object of the invention is to provide novel and improved automatic means whereby the supply of cold water to the heater, and the supply of air and gas and ignition of the latter, is controlled through the operation of the hot water faucet.

Further objects of the invention are to

provide a novel and improved water heater which is unitary and selfcontained, automatic in a high degree, convenient and effective in use, and economical in action because the greater part of the heat of combustion must pass through the water as well as through the dead air space before it can reach the atmosphere by radiation from the outer shell.

Other objects and the advantages of the invention will be apparent to those skilled in the art from a careful consideration of the following description of the preferred form of the construction embodying the invention, taken in connection with the accompanying drawings in which—

Figure 1 is a broken elevational view of the water heater; Fig. 2 is a broken cross-sectional view taken on the line 2—2 of Fig. 1; Fig. 3 is a partly whole and partly sectional view taken on the line 3—3 of Fig. 1; Fig. 4 is a cross-sectional view taken on the line 4—4 of Fig. 3; and Fig. 5 is a broken view showing the hot water faucet.

Referring to the drawings, the base 5 has thereon the burner 6. Shells 7 and 8 of suitable metal are formed and arranged on the base 5 to provide the combustion chamber 9 and the water space or chamber 10 which surrounds the combustion chamber 9. An additional shell 11 is preferably constructed and arranged on the base 5 to surround the inner shell 7 and the intermediate shell 8, and provide the dead air space or insulating chamber 12. The shells 7, 8, and 11, preferably are cylindrical and have their upper ends provided with covers or crowns 13 and have their lower ends suitably affixed on the base 5. A suitable vent or relief valve 14 is arranged in communication with the upper portion of the combustion chamber 9, and suitable piping 15 provided with the faucet 16 leads from the upper portion of the water chamber 10. The base 5 is preferably provided with an annular passageway 17 in communication with the lower part of the water chamber 10, and suitable water supply piping 18 is connected to the annular passageway 17.

As shown, automatic means operatively connected to the hydraulic motor 19 is preferably employed to control the supply and ignition of the gas fuel and air for the burner 6. On the shaft 20 of the hydraulic motor 19 is mounted fast the governor 21 the weighted arms 22 of which bear against

the shoulder 23 on the sleeve 24 which latter is rotatably and slidably mounted on the shaft 20 and is provided with a shoulder 25 between which and the frame 26 of the governor is interposed the spring 27. The sleeve 24 is provided with a head 28 which is arranged loosely in a socket 29 provided in the sleeve 30 which is mounted on the shaft 20 and is provided with an arm 31 which is pivotally connected to the lever 32 which latter has its upper end pivotally mounted on the base 5. A rod 33 has one of its ends pivotally connected to the lever 32 and has its other end connected to the piston of the valve 34 for controlling the supply of gas fuel and air to the pilot light, and a hinged rod 35 has one of its ends pivotally connected to the lever 32 and has its other end connected to the piston of the valve 36 for controlling the supply of fuel gas and air to the burner 6. A rotary air pump 37 is operatively connected to the shaft 20 and is provided with the air intake port 38 and has connected to its air discharge port 39, suitable piping 40 which leads to the tank 41 and is provided with a suitable check valve 42. The tank 41 is preferably arranged in the lower part of the dead air space 12 in order to heat the air in the tank. Suitable piping 43 and 44 leads from the air tank 41 to the valves 36 and 34, and suitable gas fuel supply piping 45 and 46 is connected to said valves 36 and 34. Suitable check valves 47 are provided in the piping 43 and 45. Suitable piping 48 is connected to the outlet port of the valve 36 and to the burner 6 to conduct the mixture of gas fuel and air from the valve 36 to the burner 6. A pipe 49 conducts gas fuel from the valve 34 to the pilot light ignition chamber 50 in the burner 6, and a pipe 51 conducts the air from the valve 34 to the blow pipe 52 which is arranged in the passageway 53 leading from the ignition chamber 50 to the upper end of the burner 6. Water under pressure—from the city service mains—is supplied to the hydraulic motor 19 by suitable piping 54 provided with valve 55, and the water passes from the motor 19 to the annular passageway 17 by way of the piping 18. In the ignition chamber 50 are arranged the electric spark points 56 and 57 which are insulated from each other and carried by the plug 58 which is screwed on the base 5. The spark point 56 is electrically connected by conductor 59 to suitable current supply source of battery 60, and the spark points 57 are connected by the conductor 61 to the contact 62 which is movable to engage the stationary contact 63 which latter is connected by the conductor 64 to the battery 60. The contact 62 is mounted on the arm 65 and is normally held away from the contact 63 by means of the spring 66 pressing against the arm 65. A roller 67 on the le-

ver 32 is adapted to bear against the arm 65 and move the latter to bring the contacts 62 and 63 together when the lever is operated through the action of the governor 21.

From the foregoing description the operation and advantages of the invention will be apparent to those skilled in the art; it being understood that when the hot water faucet 16 is opened the cold water passes through and operates the hydraulic motor 19, whereupon the governor 21 acts to move the sleeves 24 and 30 and thereby move the arm 31 which moves the lever 32 to have the roller on the latter move the arm 65 to bring together the contacts 62 and 63 so that the current supply source 60 is electrically connected to the spark points 56 and 57 to produce electric sparks in the ignition chamber 50. Movement of the lever 32 through the action of the governor 21 also effects movement of the rods 33 and 35 to open the valves 34 and 36 so that fuel gas and air may pass to the pilot light and to the burner 6. Operation of the rotary motor 37 by the hydraulic motor 19 forces the air—preferably under a pressure substantially equal to that of the gas—through the piping 40 to the tank 41 from which the air passes by way of the piping 43 and 44 to the valves 36 and 34. The air passing to the valve 36 is mixed with the fuel gas from the piping 45 and the mixture of the fuel gas and air passes by way of the piping 48 from the valve 36 to the burner 6 where it is ignited by the pilot light. The fuel gas for the pilot light passes by way of the piping 46 to the valve 34 and thence by way of the piping 49 to the ignition chamber 50 where it is ignited by means of the spark points 56 and 57 and the flame is blown over the burner 6 by the blow pipe 52 which receives air by way of the piping 51 which leads from the valve 34. The cold water passes from the hydraulic motor 19 and through the piping 18 to the annular passageway 17 where it is evenly distributed and passes upwardly in a thin layer or film through the chamber 10 and thence through the piping 15 to the hot water faucet 16. In passing through the chamber 10 the water is practically instantaneously heated because it moves in a thin layer or film in contact with a comparatively great area of heating surface provided by the combustion chamber 9, and because a very great portion of the heat generated in the combustion chamber must pass through the water and also through the dead air space 12 before it can pass to the atmosphere by radiation from the outer shell 11.

The construction which has been particularly illustrated and described admits of various changes and modifications and the use of parts without others—wherefore the right is reserved to all changes and modifications as do not depart from the spirit and scope 125 130 135 140 145 150 155 160 165 170 175 180 185 190 195 200 205 210 215 220 225 230 235 240 245 250 255 260 265 270 275 280 285 290 295 of the invention which is defined in the appended claims.

I claim:

1. A water heater, comprising the combination of a base, a burner thereon, shells mounted on the base, said shells formed and arranged to provide a closed combustion chamber, said chamber having a restricted relief vent, there being a water space surrounding the combustion chamber, and a dead air space surrounding the water space, a motor, an air pump operatively connected to the motor for supplying air under pressure to said burner, means for supplying gas fuel to said burner and means operatively connected to said motor adapted to control the supply to the burner of the gas fuel and air under pressure, substantially as set forth.
2. A water heater, comprising the combination of a base, a burner thereon, shells mounted on the base, said shells formed and arranged to provide a closed combustion chamber, said chamber having a restricted relief vent, there being a water space surrounding the combustion chamber, and a dead air space surrounding the water space, means for supplying air under pressure to said burner, means for supplying gas fuel to said burner, automatic means for controlling the supply to the burner of the gas fuel and air under pressure and automatic means

for electrically igniting the gas fuel and air supplied to the burner.

3. A water heater, comprising the combination of a base, a burner thereon, an inner shell, an intermediate shell, and an outer shell, each substantially cylindrical in form and having the upper parts thereof provided with crowns and having the lower parts thereof connected to the base, and arranged to provide a closed combustion chamber, said combustion chamber having a restricted relief vent, and there being a narrow water space surrounding the combustion chamber and a dead air space surrounding the water space, a hydraulic motor, a rotary air pump, operatively connected to the hydraulic motor for supplying air under pressure to said burner, means for supplying gas fuel to said burner, means operatively connected to said hydraulic motor, adapted to control the supply to the burner of gas fuel and air under pressure, and automatic means for electrically igniting the gas fuel and air supplied to the burner, substantially as set forth.

In testimony whereof, I have signed my name to this specification at St. Catherines, county of Lincoln, Province of Ontario, Canada, this 30th day of November A. D. 1915.

JUSTIN KAY TOLES.
